UNITED STATES PATENT OFFICE.

JAMES M. ROMBERGER, OF PITMAN, PENNSYLVANIA

COMBINATION RAILWAY-TIE.

1,034,512.

Patented Aug. 6, 1912.

Application filed March 30, 1912. Serial No. 687,368.

To all whom it may concern:

Be it known that I, JAMES M. ROMBERGER, a citizen of the United States, and a resident of Pitman, in the county of Schuylkill and State of Pennsylvania, have invented certain new and useful Improvements in Combination Railway-Ties, of which the following is a specification, reference being had to the accompanying drawings.

10 This invention has relation to certain new and useful improvements in ties used to support railroad rails and the object of my invention is to provide a composite tie including a metal frame and concrete filler including sufficient elasticity insuring the rails being properly held while further including a positive means for securing the rail to the tie.

With these and other objects in view, the present invention consists in the combination and arrangement of parts as will be hereinafter more fully described and finally pointed out in the appended claim, it being further understood that changes in the specific structure shown and described may be made within the scope of the claim without departing from the spirit of the invention.

In the accompanying drawings forming a part of this specification and in which like numerals of reference indicate similar parts in the several views: Figure 1, shows a side elevational view, with parts broken away, of the tie constructed according to my invention showing the rails in position. Fig. 2, is a section on line 2, 2 of Fig. 1. Fig. 3, is a section on line 3, 3 of Fig. 2. Fig. 4, is a top view of one end of the tie.

Most metal and composite ties are objectionable in that they are too stiff and rigid. It is found that the sleepers supporting railroad rails must possess a certain amount of give and elasticity. In my present invention I provide a railroad tie which, while of sufficient strength, possesses a sufficient amount of elasticity, so that the same can be effectively used in railroad construction.

In carrying out the aim of my invention I employ a flat metal base plate 1. Held to this base plate are two similar concrete end blocks 2, 2 each having its inner face α , angled outward from the upper edge as clearly shown in Fig. 1. Held between these two end blocks 2, 2, is a central concrete key block, 3, having oblique ends to seat against said angled faces α . As shown these blocks 2 and 3, are of a similar width

and thickness and held upon these blocks is a top plate 4, having two parallel upstanding flanges 5, 5. Held between the flanges 5, 5 is an apertured bed block 6, of a thickness equal to the height of the flanges 5, 5, two such bed blocks being used, one at each end, as shown in Fig. 1. Each bed block is provided with a lug 7, having an outstanding lip 8. A bolt 13, is employed to hold the bed blocks to the tie structure. As shown the top plate 4, the base plate 1, and the end blocks 2, have registering bolt openings, to receive the bolts 13, this construction being clearly shown in Fig. 3. Securely held to each base plate, is a clamp block 10, having a bolt opening and an outstanding lip 9.

As shown in Fig. 3, the base plate 6, the top plate 4, and the end member 2, and base plate 1, each have an opening to receive a bolt 14.

From the foregoing it will be noticed that each base plate is held to the tie by means of two bolts, while arranged to be held below the lips 8 and 9, is the base of a suitable rail A.

The central key block 3, is held between the base and top members 1 and 4, by means of a bolt 20, having a securing nut 21, this construction being shown in Fig. 1. The lugs 7, come upon the outside so that there is no danger of the rail spreading, and as disclosed in Fig. 2, the rail is held upon the flanges 5, as well as upon the base plate 6.

Owing to the angled faces α , a certain amount of elasticity is imparted to the structure, in that the blocks are permitted a movement within certain limits.

A tie constructed according to my invention is of sufficient elasticity to permit of the vibration of the rails A, so as to insure easy riding of the rolling stock over the rails. The tie is further simple and comparatively inexpensive in construction and both desirable and efficient in operation. Further the blocks can be easily replaced in case of fracture while the rails are absolutely held against casual displacement.

Having thus described my said invention, what I claim as new and desire to secure by United States Letters Patent is:

A composite tie, including a flat metal base plate, two similar concrete end blocks each having its inner face angled outward from the upper edge, a central concrete key block having oblique ends to seat against

said angled faces, a top plate having two parallel upstanding edge flanges resting upon said blocks, an apertured bed block of a thickness equal to the height of said flange with an outstanding lip located near each end of said top plate, a bolt passing through each bed block, end block and said top and base plates, an apertured clamp block upon each bed block having an outstanding lip, a bolt passing through each clamp block, bed block, top plate, an end block and base plate, a bolt passing through

said top plate central block and base plate, said lips being arranged to clamp upon the base of a suitable rail held upon said flanges and a bed block, and nuts upon said bolts to hold said members together, as and in the manner set forth.

In testimony whereof I affix my signature, in presence of two witnesses.

JAMES M. ROMBERGER.
